UNITED STATES PATENT OFFICE

170,322

DOLL

Maude P. Jones, Bremerton, Wash.

Application July 14, 1952, Serial No. 20,604

Term of patent 7 years

(Cl. D34—2)

To all whom it may concern:

Be it known that I, Maude P. Jones, a citizen of the United States, residing at Bremerton, in the county of Kitsap and State of Washington, have invented a new, original, and ornamental Design for a Doll, of which the following is a specification, reference being had to the accompanying drawing, forming part thereof.

I claim:

The ornamental design for a doll, as shown.

MAUDE P. JONES.
